UNITED STATES PATENT OFFICE.

PATRICK J. BRENNAN AND QUINTIN M. QUIGG, OF NEW YORK, N. Y.; SAID QUIGG ASSIGNS HIS RIGHT TO SAID BRENNAN.

IMPROVEMENT IN TUBE-COUPING STEAM-BOILERS.

Specification forming part of Letters Patent No. 131,390, dated September 17, 1872.

To all whom it may concern:

Be it known that we, PATRICK J. BRENNAN and QUINTIN M. QUIGG, of the city, county, and State of New York, have invented certain new and useful Improvements in Sectional Steam-Boilers; and we do hereby declare that the following is a full, clear, and exact description of the same, reference being had to the accompanying drawing making part of this specification.

This invention relates to that kind of sectional boiler which is constructed of tubes with the water inside the same. In such boilers the tubes are often arranged in an inclined position, with the ends connected through and by means of small box-shaped castings. By this plan there are usually three or more joints at each end of each tube, in order to secure the castings to the tubes and to each other in such manner as to provide communication for the steam and water. These joints are liable to leak, and must all be broken when it is desired to renew an injured tube. Our invention consists of a connecting-coupling screwing both into the tube-head and onto the tube, and arranged so that it may be operated with an inside-wrench through a hand-hole in the tube-head.

In the drawing, Figure 1 represents a front elevation of our improved boiler. Fig. 2 is a longitudinal and vertical section of the same. Fig. 3 is an enlarged front view of a section of a tube-head. Fig. 4 is a vertical longitudinal section through the tube-heads and tubes. Fig. 5 is a front view and longitudinal section of one of our improved tube-couplings.

The water-tubes designated A are preferably arranged in an inclined position, as shown in Fig. 2, with a furnace, C, under one end of the same. The ends of the tubes are secured, in a manner hereafter described, in large hollow slabs B B', called "tube-heads." The products of combustion from the furnace C are preferably conducted between the tubes up near the front tube-head B, and thence down and up between the tubes, and between properly-constructed deflecting-plates, to the rear of the boiler; thence down along the back tube-head B', and underneath it to the rear of the same; thence through fire-tubes D D, Fig. 4, arranged within the water-tubes, and more particularly described hereafter, to the front connection E;

and thence, in front of the tube-head B, to the chimney F. In the drawing but one deflecting-plate, G, is shown; but more can be employed in a well-known manner. H is a chamber for the reception of ashes and soot that may be carried over the bridge-wall or deflecting plates. a a are bearers supporting the tube-heads. I is a door, which may be opened to sweep the fire-tubes and repair the boiler. The back connection should be sufficiently wide to permit a man to work at the tubes; or may be provided with a door, the same as the front connection. The tube-heads are made generally of cast-iron. The inner and outer shells are connected by studs b b, forming part of the same casting. To secure great strength when the steam-pressure is very high we run bolts or rivets through the studs, or put in socket-bolts in the usual way. The water-tubes are secured in the inner plates of the tube-heads by couplings G, one of which is shown separately in Fig. 5. This coupling consists of a hollow cylinder or ring provided with screw-threads of the same pitch on both its inner and outer surfaces, which threads extend nearly the whole length of the cylinder. At one end the opening in the coupling is slightly reduced in size, and formed with six sides, or with any number of faces or projections, to fit an inside-wrench. The coupling G screws into the rear sheet of the tube-head and on the exterior of the tube at the same time, care being taken that the threads start the same and are of the proper taper to insure a tight joint. Opposite the ends of the tubes are hand-hole openings c c, of sufficient size to permit the removal through them of the tubes A and couplings G. These openings c c are closed by suitable bonnets or plugs d d, which, as represented, are screwed into the outer plates of the tube-heads. The fire-tubes D D are arranged inside the water-tubes, and extend entirely through them across the water-space in the tube-heads, and into the hand-hole bonnets d, each tube and bonnet being preferably secured together by a screw having the same pitch as that on the exterior of the bonnet, so that the latter, when it is put in, will screw into the tube-head and over the tube at the same time. The fronts of the bonnets d have annular projections with flat faces thereon to receive a wrench.

When it is desired, one end of each tube A

may be screwed directly into a tube-head and the other end be secured with a coupling, as shown.

It is evident that the tube-heads for a large boiler may be made up of any desired number of slabs or comparatively-narrow tube-heads containing one or more rows of tubes, which slabs would be connected together in the usual way.

By the use of the coupling G an injured tube can be readily removed from any part of the boiler without disturbing the joints on the other tubes.

We are aware that the pipe-fitters' "reducing-socket" bears some resemblance in appearance to our coupling G; but the former does not, on many sizes, have the threads on the outside and inside of the ring of the same pitch, and the threads taper to connect with pipes of different sizes from opposite ends, which is different from our device. The combination of our socket with a tube and tube-head is also new, and produces a new, useful, and desirable result.

The fire-tubes D act as stays to the front sheets of the tube-heads, and give great facilities for increasing the heating-surface of the boiler. They also enable us to conveniently carry the products of combustion on both sides of the tube-heads, and we thereby utilize as heating-surface what is cooling or radiating surface in many other boilers; also, the high temperatures on the two sides of the tube-heads entirely prevent them from being fractured by unequal expansion.

We claim as new and desire to secure by Letters Patent—

The connecting-coupling G combined with a tube and tube-head, and constructed with its opening adapted to an inside-wrench, substantially in the manner shown and described.

PATRICK J. BRENNAN.
